BOXCAR

Warren R. Elsey, Elizabeth, N. J., and Wendel J. Meyer, Philadelphia, Pa., assignors to The Pennsylvania Railroad Company, Philadelphia, Pa., a corporation of Pennsylvania

Application November 5, 1936, Serial No. 109,262

18 Claims. (Cl. 105—377)

This invention relates to box cars such as are used by railroads in shipping freight; and it has reference more particularly to box cars adapted to be loaded from above through roof hatches.

In connection with box cars of the specific type referred to, it is an aim of our invention to provide a simple and sturdy roof construction which will afford a plurality of unobstructed quadrangular hatch openings of a maximum size, and which, at the same time, will effectively tie together and brace the side and end walls of the car.

Another object of our invention is to insure against entry of rain and snow into the hatches, which desideratum we attain, as hereinafter more fully disclosed, through provision of deflector means beneath over-hanging portions of the covers for the hatch openings.

Our invention is also directed toward provision of simple and reliable latch means for securing the hatch covers capable of operation from within the body of the car.

Other objects and attendant advantages of our invention will appear in the following description of the attached drawings, wherein Fig. I shows the top plan view of a box car body conveniently embodying the present improvements, with one of the hatch covers removed and another partly broken away.

Fig. II is a fragmentary view on a larger scale showing, in elevation, a portion of one end of the car body.

Fig. III is a fragmentary cross sectional view of the car body taken as indicated by the arrows III—III in Fig. I.

Fig. IV is a fragmentary view showing the car body in longitudinal section.

Fig. V is a view on a larger scale corresponding to Fig. IV, showing the center portion of the car body.

Fig. VI is a fragmentary detail view showing one of the top corners of the car body in plan with the corresponding hatch cover removed.

Fig. VII is a fragmentary view looking as indicated by the arrows VII—VII in Figs. I and VI and showing the same corner in side elevation.

Fig. VIII is a fragmentary detail cross sectional view taken as indicated by the arrows VIII—VIII in Fig. VII.

Fig. IX is a fragmentary detail sectional view taken as indicated by the arrows IX—IX in Fig. VIII.

Figs. X, XI, XII, and XIII are fragmentary detail views taken as respectively indicated by the

arrows X—X, XI—XI, XII—XII, and XIII—XIII in Fig. I.

Fig. XIV is a fragmentary detail sectional view of the hatch cover securing means, taken as indicated by the arrows XIV—XIV in Fig. III.

Fig. XV is a fragmentary sectional view taken as indicated by the arrows XV—XV in Fig. IV showing further details of the hatch cover securing means; and

Fig. XVI is a view like Fig. IV showing an alternative form of hatch cover securing means.

In accordance with my invention, and as herein shown, the usual longitudinal Z-section eave bars 1 of the car body have secured to their upper vertical flanges in overlapping relation by means of rivets 2, inwardly curved shoulder plates 3 with upstanding flanges 4 along their tops. These curved shoulder plates 3 are backed or braced by conformative castings 5 and 6 respectively, located at suitable intervals along the interior of the car and at the corners, said castings being secured with said plates and the Z-bars 1, to the side plates 7 of the car body by the aforementioned rivets 2. To the end plates 8 of the car are riveted Z-section bars 9 (see Figs. II, IX, and X) having upright upper flanges 10 corresponding in depth to the top flanges 4 of the curved plates 3 and meeting with said flanges 4 at the body corners. The flanges 4 and 10 respectively of the curved plates 3 and the end Z-bars 9 thus jointly define the boundary of a top opening which is substantially co-extensive in length with the car body. By means of suitably-spaced arching cross members 11, the flange-rimmed opening formed in the top of the car as just explained is subdivided into a plurality of smaller serially-arranged quadrangular hatch openings 12, in the present instance, three. As shown in Figs. I and XIII, the cross members 11 are of U-cross section with their ends engaging cut-outs or notches in the flanges 4 of the curved plates 3, and supported on the tops of certain of the castings 5. It is to be noted that the vertical flanges 13 of the cross members 11 correspond in depth with the flanges 4 of the curved plates 3 and thus constitute the side edges of contiguous hatch openings 12. At the regions of meeting, the flanges 4 and 13 of the curved plates 3 and the transverse members 11 are preferably permanently united as by welding, with formation of flush transverse gutters 14 between adjacent hatch openings. The edges of the hatch openings 12 are finished off by coaming rails 15 which have an invert U-cross section as shown, and whereof the inner flanges 16 are considerably

40

45

50

deeper than the outer flanges 17, the latter flanges having edge margins bent outwardly as at 18 to serve as rain and snow deflectors in a manner more clearly described later. As shown in Figs. III, VIII, X and XII, the outer flanges 17 of the coaming bars 15 overlap and are riveted fast to the meeting upstanding flanges 4, 10 and 13 respectively, of the curved plates 3, and the Z-bars 9 at opposite ends of the car, and the transverse connecting members 11. The coaming bars 15 are stiffened by angular inward bending of their flanges 16 at the bottom as at 19, except those at the ends of the car body, whereof the flanges 16 are straight and riveted to inverted channel section cross members 20 interposed between the latter flanges and the end plates 8, see Fig. X. At their opposite ends, the cross members 20 are in turn riveted fast to projections 21 of the corner castings 6 as shown in Figs. VIII and IX. At the regions of meeting, the coaming bars 15 are all mitered and preferably welded together. Obviously, as a consequence of this construction, the side and end walls of the car body are effectively tied together and braced with attendant provision of hatch openings of a maximum size.

The hatch covers 25 are of composite construction with perimetric frames 26 formed from invert U-section rails, and roof sheets 27 riveted to said frames. The hatch covers 25 are further re-inforced by laterally spaced transverse arching channel section battens 28 extending between the side rails of the frames 26. The rails of the hatch cover frames 26 are preferably miter jointed, and the component parts of each cover frame including the battens 28 permanently united by welding at the regions of juncture. From Figs. III, X, and XI, it will be noted that the hatch cover frames 26 are so proportioned that the inner flanges of their rails 29 fit rather snugly into the hatch openings 12 defined by the coamings 15, and moreover that the frames are stiffened through outward bending of margins of said inner flanges and also of the outer flanges 30 as indicated respectively at 32 and 31. When the covers 25 are in place, the outer pendant flanges 30 of the frames 26 overhang the projections 18 around the hatch coamings 15, within perimetric clearances 33. By joint action of the outward perimetric projections 31 of the hatch covers 25 and the perimetric projections 18 of the coamings 15, rain and snow are effectively deflected and prevented from entering the car through the hatches. Each hatch cover 25 is provided, as shown in Fig. I, with four eyes 35 so that a lifting crane can be conveniently employed in removing it, and each of them, moreover, carries a portion 36 of a running board which extends centrally of the top of the car. The slats 37 of each section 36 of the running board are supported at a slight elevation above the roof sheets 27 by bridge pieces 38 riveted to the covers in the regions of the battens 28. In each instance, a channel section ridge bar 39 serves to stiffen the hatch cover longitudinally. At opposite ends of the car are additional boards 40 which constitute continuations of the main running board, and which, with similar continuations of contiguous cars of a train, bridge the gaps between cars. As shown in Figs. II and X, the supplemental end boards 40 are supported by brackets 41 riveted fast to the car ends. The endmost hatch covers also carry lateral running boards 42 whereof the slats 43 are supported by

bridge pieces, such as shown at 44 in Fig. II, suitably affixed to said covers.

The securing means for the hatch covers 25 includes a pair of shafts 45 which may be of square section as shown, and which extend longitudinally of opposite sides of the interior of the car body immediately under the curved shoulder plates 3, see Figs. III, IV, V, X, and XIII. To these shafts 45 are secured, by means of set screws 46, cylindric collars 47 which are journaled for rotation in bearings 48 afforded by the brackets 5. To each of these shafts 45 is also affixed a series of latch members 49 which extend upward into the hollows of the coamings 15 and whereof the hook ends 50 reach inwardly through clearance apertures 51 in the inner flanges 16 of said coamings and engage registering apertures 52 in the inner flanges 29 of the hatch cover frames 26. The shafts 45 are operable by means of lever handles 53 which extend downwardly from them immediately inward of the door openings 55 in the sides of the car, as shown in Figs. IV and XVI, where they are conveniently accessible. The lever handles 53 are lockable against movement, with the hatch covers 25 latched by registering eyes 55 on them with apertured lugs 56 on the car and the passing chain-supported hooks 57 (Fig. IV) through the aligned apertures of said eyes and lugs. As a consequence of this arrangement, it is possible to simultaneously latch the hatch covers at each side of the car.

In Fig. XVI there is shown a modified locking arrangement in which separate latching shafts 45a are provided at the opposite sides of the car for each hatch cover, said shafts being individually operable by separate lever handles 53a.

Having thus described our invention, we claim:

1. A box car with an opening in its top substantially coextensive in length with the car defined by upstanding edge flanges of meeting plate members of the car body; U-section cross members with upstanding flanges corresponding in depth to those of said plate members with their ends fitting notches in the longitudinal flanges of the opening and setting apart a plurality of separate hatch openings; and individually removable covers for the hatch openings.

2. A box car with an opening in its top substantially coextensive in length with the car defined by upstanding edge flanges of meeting plate members of the car body; U-section cross members with upstanding flanges corresponding in depth to those of the body members with their ends fitting notches in the longitudinal flanges of the opening and setting apart a plurality of separate hatch openings; individually removable covers with perimetric portions overhanging the hatch openings; and perimetric deflector means beneath the overhanging portions of the covers for preventing entry of rain or snow into the hatches.

3. A box car having a hatch opening in its top defined by upstanding edge flanges of meeting plate members of the car body; invert U-section coaming bars with their outer flanges fastened to the perimetric flanges around the hatch opening; a removable hatch cover having a roofing sheet and a perimetric reinforcing frame formed from invert U-section bars with the inner flanges of the latter fitting into the coamed hatch openings and with the outer flanges extending beyond the coaming; and perimetric deflector means beneath the overhanging portion of the cover

40

around the coaming beneath the cover for preventing entry of rain or snow into the hatch.

4. A box car having a hatch opening in its top defined by upstanding edge flanges of meeting plate members of the car body; invert U-section coaming bars with their outer flanges overlapping and fastened to the outsides of the perimetric flanges around the hatch opening and with edge margins of said outer flanges bent laterally outward to form a perimetric deflector for rain and snow; and a removable cover having a roof sheet, and perimetric reinforcing frame formed from invert U-section bars with their inner flanges fitting into the coamed hatch opening and their outer flanges overhanging the perimetric deflector around said opening.

5. A box car with an opening in its top substantially coextensive in length with the car defined by upstanding edge flanges of meeting plate members of the car body; U-section cross members with upstanding flanges corresponding in depth to those of said plate members with their ends fitting notches in the longitudinal flanges of the opening and setting apart a plurality of separate hatch openings; invert U-section coaming bars with their outer flanges fastened to the perimetric flanges around the several hatch openings; individually removable hatch covers respectively having roofing sheets and perimetric reinforcing frames formed from invert U-section bars with the inner flanges of the latter fitting into the coamed hatch openings and with the outer flanges extending beyond the coamings; and perimetric deflector means beneath the overhangs of the covers for preventing entry of rain or snow into the hatches.

6. A box car having a body with side and end walls; Z-bars secured along the top edges of the side walls; inwardly rounded shoulder plates secured to the upper flanges of the Z-bars, said plates having upright flanges at their tops; Z-bars fastened along the upper edges of the end walls of the car body with their upper upright flanges meeting the upright flanges of the shoulder plates to form a hatch opening; and a removable cover for the hatch opening.

7. A box car having a body with side and end walls; Z-bars secured along the top edges of the side walls; inwardly rounded shoulder plates secured to the upper flanges of the Z-bars, said plates having upright flanges at their tops; Z-bars fastened to the upper edges of the end walls of the body, the upper flanges of the last mentioned Z-bars meeting with the upright flanges of the shoulder plates; transverse U-section cross members at intervals along the length of the car body setting apart a plurality of individual hatch openings, the ends of said cross members fitting notches in the flanges of the shoulder plates with their flanges meeting those of said shoulder plates; conformative castings secured to the inner sides of the shoulder plates and supporting the ends of the cross members; and separately removable covers for the several hatch openings.

8. A box car having a body with side and end walls; Z-bars secured along the top edges of the side walls; inwardly rounded shoulder plates secured to the upper flanges of the Z-bars, said plates having upright flanges at their tops; Z-bars fastened to the upper edges of the end walls of the body, the upper flanges of the last mentioned Z-bars meeting with the upright flanges of the shoulder plates; transverse U-section cross members at intervals along the length of the car

body setting apart a plurality of individual hatch openings, the ends of said cross members fitting notches in the flanges of the shoulder plates with their flanges meeting those of said shoulder plates; conformative castings secured to the inner sides of the shoulder plates and supporting the ends of the cross members; invert U-section coaming bars having their outer flanges overlapping and secured to the upright perimetric flanges around the hatch openings; and individually removable hatch covers having roof sheets and perimetric supporting frames formed from invert U-section bars, with the inner flanges of said bars fitting into the coamed hatch openings and with the outer flanges extending beyond the coamings.

9. A box car having a coamed hatch opening; a hatch cover with a pendant perimetric flange; and means for securing the cover from within the car, including retractable latch members adapted to reach laterally through clearance apertures in the coaming and engage the pendant flange of said cover.

10. A box car having a coamed hatch opening; a hatch cover with a pendant perimetric flange; and means for securing the cover from within the car, including pivotally mounted latch members adapted to reach laterally through clearance apertures in the coaming and engage the pendant flange of the cover.

11. A box car having a coamed hatch opening; a cover with a pendant perimetric flange fitting into the hatch opening; and means for securing the cover from within the car, including retractable latch members adapted to reach laterally through lateral clearance apertures in the hatch coaming and engage the pendant flange of the cover.

12. A box car having, along its length, a plurality of coamed hatch openings; hatch covers with pendant perimetric flanges; and means for securing the covers from within the car including a longitudinally extending shaft and latch members on the shaft adapted to reach laterally through clearance apertures in the coamings and engage the pendant flanges of the covers, and means for actuating the shaft.

13. A box car having a coamed hatch opening; a cover with a pendant perimetric flange fitting over the hatch opening; and means for securing the cover from within the car including horizontal shafts parallel with the edges of the hatch opening; latch members on the shafts adapted to reach laterally through lateral apertures in the hatch coaming and engage the pendant flange of the cover; actuating lever handles for the shafts; and means for locking the actuating handles against movement with the cover latched.

14. A box car having, along its roof, a longitudinal series of coamed hatch openings; individual covers with pendant perimetric flanges fitting over the hatch openings; and means for securing the covers from within the car, including a longitudinally extending shaft; latch members on the shaft, adapted to reach laterally through clearance apertures in the hatch coamings and engage the pendant flanges of the covers; an actuating lever handle for the shaft; and means for locking the actuating handle with the covers latched.

15. A box car having a hatch opening with an upstanding perimetric flange jointly afforded by plate members of the car body structure; hatch coaming bars of invert U-section with their inner flanges fastened to the perimetric flange around the hatch opening; a cover with a pendant peri-

metric flange fitting over the coaming; and means for securing the cover from within the car, including pivotally mounted latch members extending upward into the hollow of the coaming, said latch members having hook ends adapted to reach laterally through clearance apertures in the coaming and engage the pendant flange of the hatch cover.

16. A box car having a hatch opening with an upstanding perimetric flange jointly afforded by plate members of the car body structure; hatch coaming bars of invert U-section with their inner flanges overlapping and fastened to the perimetric flange around the hatch opening; a cover with a roofing sheet and a perimetric supporting frame formed from invert U-section bars with the inner flanges of the latter fitting into the coamed opening; and means for securing the cover from within the car, including retractable latch members reaching laterally through clearance apertures in the inner flanges of the coaming and engaging the corresponding inner flanges of the perimetric frame bars of said cover.

17. A box car having, along its roof, a longitudinal series of coamed hatch openings; individual covers with pendant perimetric flanges fitting over the hatch openings; and means for securing the covers from within the car, including a series of aligned longitudinal shafts along opposite sides of the car, latch members on the respective shafts adapted to reach laterally outward through clearance apertures in the hatch coamings and engage the pendant flanges of the covers, and means for actuating the individual shafts.

18. A box car having a coamed hatch opening in its top; a cover with an outwardly and downwardly-extending perimetric flange portion overhanging the hatch coaming with a downwardly open perimetric clearance intervening; and a perimetric deflector projection extending outward laterally from the hatch coaming beneath the overhang of the cover and crosswise of the clearance interval to exclude rain or snow from said interval.
